W. P. McNEEL.
SPEED REGULATING DEVICE.
APPLICATION FILED NOV. 27, 1920.

1,416,567.

Patented May 16, 1922.

Inventor:
William P. Mc Neel
by Chas. J. O'Leill. atty.

UNITED STATES PATENT OFFICE.

WILLIAM PINKNEY McNEEL, OF SAN ANTONIO, TEXAS.

SPEED-REGULATING DEVICE.

1,416,567.

Specification of Letters Patent. Patented May 16, 1922.

Application filed November 27, 1920. Serial No. 426,845.

To all whom it may concern:

Be it known that I, WILLIAM P. McNEEL, a citizen of the United States, residing at San Antonio, State of Texas, have invented 5 certain new and useful Improvements in Speed-Regulating Devices; and I do hereby declare the following to be a full, clear, and exact description of the invention, such as will enable others skilled in the art to 10 which it appertains to make and use the same.

This invention relates to improvements in speed regulating devices, and particularly to a device for gradually increasing or decreasing 15 the speed of a driven member automatically.

The invention is applicable, and well adapted, to motion picture film apparatus, wherein it is desired to increase or decrease 20 the speed of the film reel, and is an improvement over the apparatus disclosed in one of my former Patents, No. 1,302,821, of May 6, 1919, but it is, of course, to be understood that the invention is not limited 25 to such adaptation, but will be equally effective in any form of apparatus where a gradation of speed is desired.

The particular object of the invention is the provision of a device for positively and 30 automatically gradually increasing or decreasing the speed of a driven member through a transmission of particular design and construction.

The invention, in its broadest aspects, 35 comprises a driven shaft provided with a specially designed rotatable cone member adapted to be engaged by a particularly constructed wheel member mounted on the driving shaft, the novel cooperation of the 40 cone with the wheel not only providing the necessary engagement therebetween, but also the means of guiding the wheel along and around the peripheral surface of said cone from end to end, or between any of 45 the intermediate points thereof, during the operation of the device.

The invention also contemplates an arrangement whereby the graduation in speed may be effected from the highest to the 50 lowest speeds or vice versa, or from any intermediate speed to the highest or lowest speeds, means being provided for disengaging or engaging the contacting elements of the transmission at any point within the 55 extreme range of speeds.

The particular improvement of the present invention over that disclosed in my former patent, above mentioned, is in the difference of construction and design of the contacting members of the variable speed 60 transmission whereby a positive and certain graduation of the speed is assured.

Generally stated, the improved device comprises a truncated cone journaled in a substantially U-shaped frame pivotally supported in another, oppositely disposed, U-shaped frame, which latter frame is attached to a base plate properly secured in any desired position relative to the machine, or the like, with which the aforesaid 70 device is to cooperate. The cone member is preferably provided with a series of holes or recesses arranged in spiral formation around the periphery of the cone, in a manner similar to a screw-thread construction. Cooperating with this perforated cone is a spur wheel mounted on a rotating shaft journaled in another, similar, U-shaped frame, which frame or support is also secured to the base member carrying the cone- 75 supporting frame, said spur wheel-supporting frame being arranged alongside of the cone-supporting frame and in parallel relation thereto.

The connection between the shaft supporting the spur wheel for driving the cone and the main driving shaft is effected through a slotted sleeve surrounding one end of the spur wheel shaft, said spur wheel shaft being provided with a pin or stud 80 adapted to project through and engage the slotted portion of said sleeve. The slot in the sleeve is of sufficient length to permit the spur wheel and its shaft to traverse the full length of the cone and allow the stud 95 or pin to be at all times in engagement with said slot. The frame-carried cone, being pivoted with respect to the mounting of the spur wheel shaft, will provide for the swinging of the cone out of and into engagement with the spur wheel, at will, according to the necessary requirements.

As one exemplification of the invention and the preferred form of device, reference may be had to the accompanying drawings, 105 in which—

Fig. 1 is a front elevation thereof,

Fig. 1^a shows the continuation of the slotted, telescoping, sleeve connection between the spur wheel shaft and main driving shaft. 110

Fig. 2 is a side view of the device, and
Fig. 3 is a top plan view thereof.

Referring to the drawings in detail, the novel transmission comprises a truncated cone 1 adapted to be driven by a cooperating wheel 2. The cone 1 is secured to the shaft 3 mounted for rotation in a substantially U-shaped frame 4, which frame is, in turn, supported, for a limited swinging movement, in another, oppositely disposed, U-shaped frame 5 by means of pivots or the like 6. The supporting frame 5 is rigidly secured to a base plate 7, which base plate may be attached in any convenient location relative to the apparatus with which the device is adapted to cooperate. The wheel 2 is secured to a shaft 8 mounted for rotation in another, substantially U-shaped frame 9, which frame is also secured to the base plate 7 alongside of and in parallel relation to the frame 5 carrying the cone-supporting frame 4. The upper end of the rotating shaft 8 is provided with a telescoping sleeve 10 which sleeve is secured by an appropriate coupling 11 to the main driving shaft 12. The sleeve 10 is constructed with a slot 13 adapted to cooperate with a pin or stud 14 carried by the shaft 8, providing the necessary means of locking the sleeve 10 to the shaft 8 for the purpose of forming the driving connection for rotating said shaft 8 during the operation of the device.

The cone 1 is provided with a series of uniformly spaced, spirally arranged, apertures or recesses 15 running around the peripheral surface of the cone from end to end. These perforations or recesses are adapted to be engaged by spurs or studs 16 mounted on the peripheral surface of wheel 2, furnishing a novel means of rotating the cone 1 by the spur wheel 2 through the shaft 8, sleeve connection 10, and main driving shaft 12, when the cone is in engagement with said spur wheel. This pin and recess construction not only provides a positive means of driving the cone but, at the same time, causes the spur wheel to be uniformly fed up and down the cone, as the case may be, in a constant and uniform manner. In other words, the particular cooperation between the cone and the driving spur wheel forms a novel interlock therebetween, and by reason of having the perforations or recesses in the cone spirally arranged an additional object will be accomplished, in that said spur wheel will be conducted up and down the peripheral surface of the cone and thereby gradually increase or decrease the speed of the cone-supporting shaft 3, connected by a universal joint or the like 17 to the driven shaft 18, said latter shaft running to the mechanism to be operated at the variable speeds.

Slot 13 in the sleeve 10, surrounding the upper end of the shaft 8, is made sufficiently

long to allow the pin or stud 14 to freely travel up and down the slot without interruption to permit the spur wheel 2 to traverse the full length of the cone from end to end during the operation of the device. 70

The legs of the U-shaped supporting frame 5 extend under the legs of the U-shaped supporting frame 4 carrying the cone shaft 3, and normally in parallel relation thereto, in order that said frame 4 will have 75 adequate support at all times. The legs of the support 5 extend well under the legs of support 4 to a point beyond the shaft 3, so that shaft 3 also passes through openings formed in said legs. The openings in 80 the legs of the support 5 are elongated as at 19, which provides for a limited swinging movement of the frame 4 on its pivots 6 when it is necessary to disengage the cone from the spur wheel. To assist in this operation, the frame 4 is conveniently provided with a handle 20 so that the cone 1, supported in said frame, can be readily moved at will, into and out of engagement with the spur wheel 2, according to requirements incident to the range of speed desired. 85

As illustrated in the accompanying drawings, the holes 15 in the cone 1 are circular in shape and, likewise, the engaging spurs 95 or pins 16, but of course it is perfectly obvious that the holes and pins may be of any appropriate shape and size.

This construction may also be reversed, and pins or spurs placed upon the cone, 100 and the periphery of the cooperating wheel provided with holes or recesses, or any other similar arrangement as desired. It is likewise within the scope of the invention to mount the cone upon the driving shaft and 105 the wheel upon the driven shaft, but the construction as disclosed has been found to be the most practical one for the purpose intended.

What I claim is:

1. In a device of the character described, the combination with a driven shaft and a driving shaft, of a cone carried by the driven shaft, a disc or wheel secured to the driving shaft, holes or recesses spirally arranged around the periphery of said cone in a uniform manner from end to end thereof, uniformly spaced spurs or pins mounted upon the periphery of said wheel adapted to engage with the holes or recesses in the cone for rotating said cone, and also providing means for automatically feeding the wheel along the cone, to cause a gradual increase or decrease in the speeds of the driven shaft, a sliding, telescoping connection between the spur wheel driving shaft and a main driving or power shaft, and means for swinging the cone into and out of engagement with the cooperating spur wheel. 110

2. In a device of the character described, the combination with a driven shaft and a driving shaft, of a cone carried by the driven shaft, a disc or wheel secured to the driving shaft, a swinging frame supporting said driven shaft and cone, a rigid frame supporting said driving shaft and wheel, holes or recesses spirally arranged around the periphery of said cone in a uniform manner 5 from end to end thereof, uniformly spaced spurs or pins mounted upon the periphery of said wheel adapted to engage with the holes or recesses in the cone for rotating said cone, and also providing means for 10 automatically feeding the wheel along the cone, to cause a gradual increase or decrease in the speeds of the driven shaft, a sliding, telescoping connection between the spur wheel driving shaft and a main driving or 15 power shaft, and means for swinging said cone-supporting frame to engage and disengage the cone and cooperating spur wheel. 20
3. In a device of the character described, the combination of a driven shaft, a driving shaft, and a supporting base plate for said device, of a cone carried by the driven shaft, a disc or wheel secured to the driving shaft, a substantially U-shaped rigid frame, attached to the base plate rotatably supporting said driving shaft and wheel, a relatively 25 larger U-shaped rigid frame also attached to said base plate adjacent to and parallel with said first mentioned frame, a substantially U-shaped swinging frame rotatably supporting said driven shaft and cone, a 30 pivotal connection between said swinging frame and said larger rigid frame, and means carried by said swinging frame for manually moving, at will, the cone into and out of engagement with the cooperating 35 spur wheel. 40

In testimony whereof I affix my signature.

WILLIAM PINKNEY McNEEL.
